PROCESS OF COOLING SPRAY DRIED
DETERGENTS

Lowell A. Ledgett, Ridgewood, and Charles W. Deane, Summit, N. J., and John J. Mahoney, New York, N. Y., assignors to Colgate-Palmolive-Peet Company, Jersey City, N. J., a corporation of Delaware

Application April 23, 1948, Serial No. 22,808

5 Claims. (Cl. 209--11)

1

The present invention relates to an apparatus for and a method of cooling spray dried organic detergents.

Spray dried organic detergents are prepared by introducing an aqueous solution of the detergent into the upper end of a spray tower through an atomizing device which breaks the liquid up into droplets. During their fall through the tower these droplets are exposed to heated air or other gas, which dries them into solid particles. The evaporation of the moisture prevents the particles from becoming heated to the temperature of the drying gas, but in normal operation soap particles leave the tower at a temperature within the range of about 170 to 195° F. while synthetic detergent particles leave at about 200 to 220° F.

Detergent particles would cake into large lumps if they were packaged at such an elevated temperature. The present invention has for an object the cooling of these hot detergent particles to a lower temperature at which the tendency to cake is minimized or overcome. The invention also contemplates transporting and/or classifying the particles simultaneously with the cooling thereof. Other objects and advantages of the invention will become apparent from the following detailed description taken in conjunction with the drawings in which:

Fig. 1 is a schematic elevational view of apparatus embodying the present invention;

Fig. 2 is a plan view with parts broken away to reveal structural details of the classifying device shown in Fig. 1;

Fig. 3 is a sectional view along the line 3--3 of Fig. 2 looking in the direction of the arrows and;

Fig. 4 is a fragmentary elevational view of the classifying device.

Referring now more particularly to Fig. 1, the apparatus comprises a tower 1 of the counter-current type, having a plurality of spray nozzles 2 in the upper portion thereof to which the liquid detergent material is pumped through line 3 by pump 4. The bottom of the tower is in the form of a cone 5 leading to an outlet pipe 6. The outlet pipe 6 communicates with a pneumatic conveyor duct 7 having an air inlet 8 and leading to a cyclone separator 9, where the product is separated from the air stream. A concurrent type tower may also be used, in which case tower air rather than atmospheric air is used in duct 7. The product leaves the separator through a product outlet pipe 10. The air stream is withdrawn through exhaust line 11 and bag house 12 by means of a fan 13 which places the entire system from the air inlet 8 through the bag house 12 under a negative pressure.

2

The product leaving the cyclone separator 9 through product outlet pipe 10 flows through star valve 10a into a surge hopper 14 having a feed leg 15 communicating with a pressure air duct 16 which leads to the bottom of a cooling column 17. The column 17 has a substantially larger diameter than the air duct 16. An outlet duct 18 leads from the top of the cooling column to a cyclone separator 19 which has a product outlet line 20 provided with a star valve 20a and an air exhaust line 21 which communicates with the exhaust line 11.

The invention also contemplates the introduction of the spray dried product from the spray tower directly into the pressure air duct 16, which eliminates the air conveyor 7 and associated parts 9, 10, 14 and 15. In such a system the tower cone 5a discharges the product through an outlet pipe 6a having an air lock, e. g., a star valve 6b, for transferring the product from the lower pressure zone of the tower into the higher pressure zone of the air duct 16.

Air under positive pressure is supplied to the duct 16, for example, by means of a positive displacement blower, or compressor or turbo-compressor 22. This air may be conditioned so as to facilitate the cooling of the product. The conditioning system illustrated in the drawing comprises a water cooler 23, which is adapted to remove the heat of compression, an evaporator 24 and a mist separator 25. Liquid refrigerant is supplied to the evaporator 24 through a liquid refrigerant line 26 and the refrigerant after evaporation in the evaporator 24 is withdrawn through a vapor line 27 to a compressor 28 driven by a motor 29. The compressed vapor flows through a condenser 31 which is provided with a water inlet pipe 32 and a water outlet pipe 33.

The cooled or partially cooled product from the separator 10 is introduced into a classifier 34. The invention also contemplates introduction of partially cooled product from the separator 9 directly into classifier 34. Referring now more particularly to Figs. 2, 3 and 4, it will be seen that the classifier comprises a bed 35 on which a framework 36 is mounted in bearings 37 at one end and in an eccentric 38 driven by a motor 39 at the other end which is at a higher level. Mounted in the framework 36 is a coarse screen 40 e. g., about 20 mesh, and fine bottom screen 41 e. g., about 150 mesh. Below the bottom screen is a dust chute 42 and above the top screen is a top wall 43, thus enclosing the screens within a housing.

The chamber within the classifier communicates with the exhaust system 11 through a plu-

arity of suction ducts 44 in the top wall 43, a manifold 45 and a suction line 46.

Air may be introduced into the space between the screens through a conditioning air system comprising an air intake 47 in which are mounted evaporators 48. Liquid refrigerant flows into evaporators 48 through line 49 and the evaporated refrigerant returns through vapor line 50. The air stream, after passing over the evaporators 48, is divided and flows through two branch lines 51 which lead to manifolds 52 on each side of the classifier. A plurality of air ducts 53 run from each manifold through the respective side walls of the classifier into the space between the screens 41 and 41 as shown in Fig. 3. The classifier is provided with a tailings outlet 54 for the oversized particles, a product outlet 55 for the particles within the desired size range and a fines outlet 56 for the particles which are of smaller size than desired. All of the ducts which connect to the classifier are provided with flexible connectors 57 to prevent the vibration of the framework 36 from traveling into the fixed lines.

The fines collected in the bag house 12 are returned for reprocessing by means of a conveyor belt 58. A similar belt (not shown) may be provided at the fines outlet 56 and the tailings outlet 54. The product discharged from line 55 may go directly to packaging apparatus.

In the operation of the apparatus, the hot spray dried product which is discharged from the tower 1 may be partially cooled by contact with ambient air in the air conveyor system using an induced draft fan to produce a rapidly moving stream of air which will entrain and convey the particles by reason of the velocity alone. A satisfactory velocity for this purpose lies within the range of about 30 to 70 feet per second. The period of contact between the air and the hot particles is limited to a few seconds by the useful length of the duct employed, but within that time the particles may be cooled to 125° F., or somewhat lower depending upon the temperature and humidity of the ambient air. A major disadvantage of an air conveying system such as that illustrated in 7, 8, 9, 10 and 11, 12 and 13 of Fig. 1 is that if the product is cooled therein to a safe packaging temperature it becomes sufficiently brittle to break up and produce excessive amounts of fines under the relatively high impact to which it is necessarily subjected in going around bends in the system and in the separator 9. This disadvantage is avoided in the practice of the present invention by only partially cooling with conveying air, or preferably avoiding its use entirely, and cooling to final packaging temperature or thereabouts in a positive air delivery low velocity system, e. g., a system embodying the principles of that shown at 16, 17, 18, 19, 20, 22, 23, 24 and 25 of Fig. 1.

The system utilizing the column or tower 17 has great merit even where cooling is merely an incident to conveying of frangible particles. In this system the air stream has sufficient area in cross section that the rate of air flow, as computed on the empty tower or duct section, is very materially less than is operable for an air-conveying system. Instead of carrying the detergent particles along by entrainment in an air stream moving at a substantially higher speed than the highest terminal velocity (i. e., the maximum velocity attained by a freely falling particles in still air) of the particles, the air fluidizes the mass and apparently either operates like

an air lift pump or operates by virtue of pressure differentials sufficient to cause low velocity flow of the fluidized mass or perhaps functions partially in both ways. The lower velocity of the air stream has the advantage not only of reducing the breakage of the particles but also of prolonging the time of contact so that the cooling effect of the air is utilized more efficiently. Satisfactory results have been obtained with a system such as that illustrated in Fig. 1, where the air velocity in the cooling column 17 falls within the range of about 3 to 16 feet per second. Lower and higher velocities may be used if desired, a practical minimum being about 0.25 feet per second, and the maximum being less than that at which a substantial proportion of the particles become air conveyed. A safe practical maximum is about 25 feet per second.

It is essential to the satisfactory operation of the lower velocity cooling system that means be provided which will build up a steep pressure gradient behind the mass of particles being treated. As the velocity is lower than that used in air conveying, particles may deposit in various portions of the system in such quantities that air pressure far in excess of that obtainable by suction alone may be required to start the particles moving again. In the positive air delivery system utilizing a positive displacement blower, for example, the necessary pressure develops automatically as the blower continues to operate.

The compression of the air by a positive displacement blower results in a temperature rise due to the heat of compression. This heat is readily removed by a water cooled heat exchanger. When this compressed air expands again to atmospheric or subatmospheric pressure, it exerts a cooling effect upon the particles with which it is in contact in the tower 17. Under certain atmospheric conditions this may be sufficient conditioning for the treating air, but under conditions of high temperature and high humidity it is often necessary to supply additional artificial cooling which also dehumidifies that air. The evaporator 24 is provided for this purpose and it is preferred to operate with the temperature of the heat exchange surface just above freezing so that the coils do not have to be defrosted. As the air becomes saturated with moisture upon cooling to lower temperatures, the excess precipitates as droplets on the cooling coils from which it can be readily drawn off. Any droplets which are entrained in the air stream can be removed by any convenient means such as the mist separator 25.

Additional cooling may be accomplished in the classifier 34 using either ambient or conditioned air, depending upon atmospheric conditions. In the process of the present invention in which the particles being classified are passed generally downward through the classifier screens, the cooling air is introduced transversely into the stream of falling particles above the bottom screen and turns upward through the upper screen into the exhaust system. The rate of flow of the cooling air is preferably such that most of the fines do not become air borne but pass through the lower screens into the dust chute 42.

The following examples will illustrate the flexibility and mode of operation of the present invention.

Example I

Spray dried soap is produced in tower 1 at a rate of about 12,200 pounds per hour from which it is discharged at a temperature of about 208° F.

It is picked up in a stream of ambient air at about 69° F. (wet bulb 66° F.) flowing through the air conveyor at about 73 feet per second. The soap which is separated from the air stream in cyclone separator 9 flows through parts 10, 10a, 14 and 15 into the duct 16 and cooling tower 17 at a temperature of about 116° F. Here it comes in contact with refrigerated air at a temperature of about 54° and a relative humidity of 94%. This air has a velocity in the column of about 5 feet per second (computed on the basis of an empty tower). The soap leaves tower 17 at a temperature of about 91° F. and with a loss of about 0.6% moisture. It passes through the classifier where tailings and fines are removed without blowing additional air into contact with the soap. The packaged product has no tendency to cake during storage.

Example II

Spray dried soap is passed at a rate of about 13,000 pounds per hour and at a temperature of about 122° F. into the cooling column. The ambient air, which has a temperature of 95° F. and a relative humidity of 60%, is cooled to about 74° F. for introduction into the cooling column and the classifier. The soap is cooled to about 105° F. in the cooling column by blowing the cooled air through it at a velocity of about 15 feet per second. Further cooling to about 90° F. is effected in the classifier by blowing the cooled air into the space between the screens at a rate of about 70 cubic feet per second. The packaged product remains free flowing on storage.

Although the invention has been described and illustrated in connection with specific illustrations of apparatus and process conditions, modifications and variations within the scope of the appended claims are contemplated.

What is claimed is:

1. The process which comprises introducing hot spray-dried organic detergent particles through an air lock into a cooling system and feeding them to the bottom of a mass of such particles, passing cooling air under positive delivery upwardly through said mass of particles in said system at a velocity less than 25 feet per second, removing cooled detergent particles from the upper portion of said mass, conveying said removed particles to an air separating device, and separating said particles from said air in said separating device.

2. The process of cooling spray-dried organic detergent particles which comprises discharging the particles from a spray tower into a current of ambient air moving at a velocity of about 30 feet to 70 feet per second in an upward direction, separating the particles from the air after a few seconds contact, introducing the particles through an air lock into a cooling system and feeding them to the bottom of a mass of such particles, passing cooling air under positive delivery upwardly through said mass of particles in said system at a velocity less than 25 feet per second, removing cooled detergent particles from the upper portion of said mass, conveying said removed particles to an air separating device, and separating said particles from said air in said separating device.

3. The process which comprises introducing spray dried organic detergent particles from a spray tower through an air lock into a cooling system and feeding them to the bottom of a mass of such particles, passing air under positive de-

livery upwardly through said mass of particles in said system at a velocity less than 25 feet per second, removing detergent particles from the upper portion of said mass, conveying said removed particles to an air separating device, and separating said particles from said air in said separating device.

4. The process which comprises introducing spray dried detergent particles at a temperature too high for packaging through an air lock into a cooling system, partially cooling said spray dried detergent particles by blowing cooling air under positive delivery upwardly through a mass of said particles in said system at a velocity less than 25 feet per second, continuously adding hot particles at the bottom of said mass, continuously removing partially cooled particles from the top of said mass, and classifying the removed particles into product, tailings and fines while blowing additional cooling air transversely into and upwardly through a stream of falling particles to complete cooling them to the desired temperature.

5. The process of cooling spray dried organic detergent particles which comprises introducing particles discharged from a spray tower and while still at a temperature too high for packaging into a current of ambient air moving at a velocity of about 30 feet to 70 feet per second in an upward direction, separating the particles from the air after a few seconds contact, passing the particles downwardly through a plurality of sloping classifying screens, passing streams of cooling air from opposite sides transversely into the stream of particles above the bottom screen and withdrawing the air upwardly through the upper screen.
